Attorney.

UNITED STATES PATENT OFFICE.

EDWARD DAVOCK, OF NEW YORK, N. Y.

INTERPOSED WATER HEATER.

1,407,989.

Specification of Letters Patent. Patented Feb. 28, 1922.

Application filed December 27, 1920. Serial No. 433,250.

To all whom it may concern:

Be it known that I, EDWARD DAVOCK, a citizen of the United States, residing at New York, in the county and State of New York, have invented certain new and useful Improvements in Interposed Water Heaters, of which the following is a full, clear, and exact specification.

This invention relates to water heaters for general or domestic use in connection with steam boilers, and it has for its object to combine a water heater with a steam boiler in an improved manner, whereby the heat which usually passes up the chimney and is lost may be utilized for heating the water for domestic or any other desired use, and the supply of hot water for such purposes may be provided as a result of the ordinary operation of a steam boiler without any additional expense for fuel or attention.

The water heating attachment is especially designed for steam boilers of the vertical sectional type, but may also be used with other styles. The invention will be herein-after described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a longitudinal central sectional view of a sectional boiler of ordinary construction having my improved water heating system installed in the flue at the rear end thereof.

Figure 2 is a section on the line II—II of Figure 1, and

Figure 3 is a section on the line III—III of Figure 1.

The boiler may be composed of a plurality of vertical transverse sections 1 mounted upon a brickwork foundation 2 and each having water passages 3 extending vertically at its sides and transverse water passages 4 alternating with passages 5 for the products of combustion. Said passages 5 of the several sections 1 constitute continuous longitudinal horizontal passages or flues which communicate with each other via a passage 6 in the front section. Each section also has a fire space 7 above the grate 8, and an ash space 9 below said grate. The front of the boiler is finished off with a front plate 10

having a fire door 11 leading to the fire chamber, and an ash door 12 communicating with the ash pit. Each section is further provided with a steam space 13 at its upper end, said steam spaces in the several sections being connected up with one another by 60 thimbles 14 fitted in registering openings 15.

Water is supplied to the water passages 3 of the sections 1 near the bottom thereof by 65 pipes 16 and circulates through said passages 3 and the transverse water passages 4 communicating therewith, as indicated by the double headed arrows in Figure 2, until it reaches the steam dome composed by the 70 communicating steam spaces 13 at the top of the boiler where the steam separates from the water and escapes through the pipes 17. The products of combustion pass from the rear end of the fire box into the 75 flue space 18 at the back of the boiler, thence through the lower of the passages or flues 5 to the front of the boiler, thence upward through passage 6 in the front section, and thence rearward in the upper flue 5 to the 80 flue space 19 at the rear end of the boiler, as indicated by the single headed arrows in Figure 1.

At the rear end of the boiler there is a 85 casing 20 supported upon a brickwork foundation 21, and vertically and transversely arranged in said casing is a chambered partition 22 constituting the rear walls of the flue spaces 18 and 19 already referred to, said flue spaces being separated from one 90 another by a horizontal transverse partition plate 23 bolted or otherwise secured to the front wall of said chambered partition 22 between the lower and upper boiler flues 5 and extending from said chambered partition to meet the rear face of the rearmost section of the boiler, as clearly shown in Figure 1. The chambered partition 22 constitutes the auxiliary water heater in which 95 water is heated by the products of combustion on their way to the chimney. After reaching the flue space 19, as already explained, the products of combustion pass through a passage 24 in the upper portion of the chambered partition of water heater 100 22 into another flue space 25 at the rear of said partition or water heater, and thence downward in the casing 20 to the chimney 26 which communicates with said casing and rear flue space 25 near the bottom thereof, as 105 110 also indicated by single headed arrows in Figure 1.

It will thus be seen that the products of combustion pass over both the front and rear faces or walls of the chambered water heating partition 22 in the casing 20 at the rear of the boiler before escaping to the chimney. During the passage of the products of combustion through the flue spaces 18, 19 and 25, the heat which is usually wasted up the chimney in the ordinary form of steam boiler is utilized for heating the water in the chambered partition 22. Water may be fed to said chambered partition 22 from a storage tank 27 arranged in any suitable point via a pipe 28, Figure 1, which enters the said partition 22 near the bottom. From the top of said chambered partition 22 the heated water passed to the storage tank through the pipe 29 preferable extending up inside the tank nearly to the top thereof so that hot water may be available almost instantaneously after the fire is started in the boiler or the water is supplied to the auxiliary water heater 22. To increase the efficiency of the auxiliary heater, series of vertical water circulating pipes 30 and 31 are arranged on the front and rear faces or walls of the chambered partition, the front pipes 30 being arranged in the flue space 18, and the rear pipes 31 being located in the flue space 25. Cold water may be supplied to the storage tank 27 via a pipe 32 entering the top of the tank and extending down nearly to the bottom thereof so as to permit the chill to be taken off of the entering water before it actually enters the tank. The hot water is delivered to any desired point or points from the tank via pipe 33, the course of the water in the auxiliary heater and storage tank being indicated in Figure 1 by triple headed arrows. A blow off pipe 34 is also provided in the tank 27 for cleaning the latter when desired.

It will be noted that the chambered partition or auxiliary water heater, and its pipes 30 and 31, which may be arranged in staggered relation as indicated in Figure 3, are placed in the midst of the hot products of combustion, and that while the pipes 30 are somewhat shorter than the pipes 31, owing to the position of the horizontal partition 23, said shorter pipes, being located in the hottest part of the flue directly behind the fire pot of the boiler, will give just as efficient service as the longer pipes 31 on the rear wall of the chambered interposed heater 22.

What I claim is:

1. The combination with a steam generator having a flue space leading to the chimney, and a plurality of horizontal flues through the body of the generator communicating with said flue space, of a chambered partition interposed across the path of the products of combustion from the generator flues to the chimney, there being a passage for the products of combustion through the

partition, said chambered partition extending transversely to the generator flues, an auxiliary partition extending from the chambered partition to the generator between adjacent horizontal flues for the purpose specified, and means for circulating water through said chambered partition.

2. The combination with a steam generator having a flue space leading to the chimney, and a plurality of horizontal flues through the body of the generator communicating with said flue space, of a chambered partition interposed across the path of the products of combustion from the generator flues to the chimney, there being a passage for the products of combustion through the partition, an auxiliary partition extending from the chambered partition to the generator body between adjacent horizontal flues therein for directing the products of combustion through said horizontal flues, water tubes communicating with the interior of the chambered partition and extending therefrom into the flue space below said auxiliary partition for the purpose specified, and means for circulating water through said chambered partition.

3. The combination with a horizontal steam boiler having a rear flue space in communication with the fire pot and horizontal flues thereof, of a chambered partition arranged in said rear flue space across the path of the products of combustion traveling to the chimney, there being a passage through said chambered partition for the passage of the products of combustion therethrough, water tubes communicating with the interior of the chambered partition and projecting therefrom adjacent the opening of the fire pot into said rear flue space, and means for circulating water through said chambered partition and tubes.

4. The combination with a steam generator having a flue space leading to the chimney, and a plurality of horizontal flues through the body of the generator communicating with said flue space, of a chambered partition interposed across the path of the products of combustion from the generator flues to the chimney, there being a passage for the products of combustion through the partition and so arranged as to compel them to pass over both faces of said partition before reaching the outlet to the chimney, said chambered partition extending transversely to the generator flues, an auxiliary partition extending from the chambered partition to the generator between adjacent horizontal flues for the purpose specified, and means for circulating water through said chambered partition.

5. The combination with a steam generator having a flue space leading to the chimney, and a plurality of horizontal flues through the body of the generator communi-

cating with said flue space, of a chambered partition interposed across the path of the products of combustion from the generator flues to the chimney, there being a passage 5 for the products of combustion through the partition and so arranged as to compel them to pass over both faces of said partition before reaching the outlet to the chimney, an auxiliary partition extending from the 10 chambered partition to the generator body between adjacent horizontal flues therein for directing the products of combustion through said horizontal flues, water tubes communicating with the interior of the 15 chambered partition and extending therefrom into the flue space below said auxiliary partition for the purpose specified.

6. The combination with a horizontal steam boiler having a rear flue space in com-

munication with the fire pot and horizontal 20 flues thereof, of a chambered partition arranged in said rear flue space across the path of the products of combustion traveling to the chimney, there being a passage 25 through said chambered partition for the passage of the products of combustion therethrough, said passage being so arranged as to compel said products of combustion to pass over both sides of the partition, water tubes communicating with the interior of 30 the chambered partition and projecting therefrom adjacent the opening of the fire pot into said rear flue space, and means for circulating water through said chambered 35 partition and tubes.

In testimony whereof I have signed my name to this specification.

EDWARD DAVOCK.
